WITNESSES.

UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 12,967, dated June 13, 1882.

Application filed April 24, 1882. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of a script letter of the class known as "back-hand," shaded upon the right and bottom by a heavy line, followed by a lightline, and ornamented by a groundwork of curved tendrill-like ornaments, as shown. In addition to the curved tendrill-like ornaments which constitute the groundwork, as shown, the curved tendrill-

like ornaments shown upon the right and left of the U, V, W, X, Y, and Z are also employed to ornament the letters of the font. ²⁰

The lower case of the font is composed of the letters, as shown, shaded upon the left by the light lines, which form, as it were, continuations of the letters and connect them together. ²⁵

Having now described my invention, I claim as new—

The design for a font of printing-type, as shown and described.

HERMAN IHLENBURG.

In presence of—

C. F. HUCH,

A. SIDNEY DOANE.
